(**) Term: **14 Years**

(57) **CLAIM**

(21) Appl. No.: **29/336,893**

The ornamental design for the turn signal light of motor
vehicles, as shown and described.

(22) Filed: **May 12, 2009**

DESCRIPTION

(51) **LOC (9) Cl.** **26-06**

FIG. 1 is a perspective view of the turn signal light of motor
vehicles showing my design;

(52) **U.S. Cl.** **D26/28**

FIG. 2 is a right elevational view thereof, the left elevational
view being a mirror image thereof;

(58) **Field of Classification Search** D26/28-36;

FIG. 3 is a front elevational view thereof;

362/459-468, 475-478, 485-487

FIG. 4 is a rear elevational view thereof;

See application file for complete search history.

FIG. 5 is a top plan view thereof; and,

FIG. 6 is a bottom plan view thereof.
